(57) **CLAIM**

I claim the ornamental design for a control panel for exercise equipment, as shown and described.

DESCRIPTION

FIG. 1 is a front perspective view of a control panel for exercise equipment;

FIG. 2 is a front view of the control panel of FIG. 1;

FIG. 3 is a side view of the control panel of FIG. 1;

FIG. 4 is a rear view of the control panel of FIG. 1;

FIG. 5 is a top view of the control panel of FIG. 1; and,

FIG. 6 is a bottom view of the control panel of FIG. 1.

The ornamental design that is claimed is shown in solid lines in the drawings. The broken (dashed) lines shown in the drawings are included for the purpose of illustrating environmental elements only and form no part of the claimed design.

The dot-dash broken line defines the bounds of the claimed design and forms no part thereof.
